ASH RECEPTACLE

William L. Davis and James V. Vevirit, Kenmore, N.Y.,
assignors to McDonald Products Corporation, Buffalo,
N.Y.

Filed May 2, 1960, Ser. No. 60,395

Term of patent 14 years

(Cl. D85—2)

Fig. 1

Fig. 2

Fig. 3

Fig. 4

FIG. 1 is a perspective view of an ash receptacle, in closed position, showing our new design;

FIG. 2 is a top plan view thereof, in closed position;

FIG. 3 is an end elevational view thereof, in closed position; and

FIG. 4 is an end elevational view thereof, in open position.

This application is a continuation-in-part of our co-pending application Serial No. D-56,467, filed June 22, 1959, and now abandoned, for a design for an ash receptacle.

We claim:

The ornamental design for an ash receptacle, substantially as shown and described.
